UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAYBOLT STRUCTURE.

1,364,150.

Specification of Letters Patent.

Patented Jan. 4, 1921.

Application filed September 12, 1919. Serial No. 323,362.

To all whom it may concern:

Be it known that we, BENJAMIN E. D. STAFFORD and ETHAN I. DODDS, citizens of the United States and residents of Pittsburgh, in the county of Allegheny and State of Pennsylvania, have invented certain new and useful Improvements in Staybolt Structures; and we do hereby declare the following to be a full, clear, and exact description 10 of the invention, such as will enable others skilled in the art to which it appertains to make and use the same.

This invention relates to improvements in staybolt structures for boilers,—objects of 15 the invention being to provide a universally movable or adjustable mounting for the head of a staybolt whereby the accurate alinement of the staybolt with its points of connection with the respective boiler sheets 20 shall be insured regardless of differences in angularity of the inner and outer boiler sheets relatively to each other; to provide an efficient bearing member for the rounded head of a staybolt; to so mount such bearing member within a sleeve that it shall be 25 capable of movement, and to construct the bearing sleeve in such manner as to facilitate the escape of sediment or incrustation.

With these and other objects in view, the 30 invention consists in certain novel features of construction and combinations of parts as hereinafter set forth and pointed out in the claims.

The accompanying drawing is a sectional 35 view of a staybolt structure showing an embodiment of our invention.

1 represents an outer boiler sheet which may be the inclined roof sheet of a boiler, and 2 a horizontal inner boiler sheet.

40 The roof sheet is provided with a bolt opening 3 a portion of the wall of which is curved transversely of the thickness of the sheet, while the inner or lower end of said opening may be made somewhat flaring.

45 A bearing sleeve or member 4 is mounted in the opening in the boiler sheet and has a general tapering shape, the lower or inner portion of said sleeve having a curved or rounded exterior portion 5 whereby the 50 sleeve may have a universally movable bearing on the curved wall of the opening in the boiler sheet.

At its lower or inner end, the bearing sleeve is provided with an inwardly inclined 55 annular flange 6 having an inclined or bev-

eled under face 7 and an outer curved face 8.

A staybolt 9 enters the sleeve 4 and its head 10 is disposed within said sleeve, while the opposite end of said bolt is suitably secured to the inner boiler sheet 2. The head 60 of the bolt may be rounded and between said head and the annular flange 6 at the lower or inner end of the bearing sleeve, an annular bearing member 11 is located. This bearing member may be made in the form 65 of a tapering ring having a curved seat 12 in its smaller end for the accommodation of the rounded head of the bolt, and having a beveled face 13 at its larger lower or inner end to freely engage the beveled face 7 of 70 the flange 6. Thus it will be seen that the bolt head has a rocking mounting upon the annular bearing member 11 and that the latter may have a movement on the flange 6.

The flaring throat formed by the flange 6 75 affords ample play to accommodate the "swing" of the bolt and by making the wall of this throat curved or rounded, as at 8, the escape of incrustation or sediment expelled by the movements of the bolt will 80 be facilitated.

The upper or outer end portion of the sleeve 4 is threaded interiorly to receive a plug or closure 14 which may be made hollow to accommodate the bolt head and 85 afford clearance therefor. The plug or closure is made with an angular portion 15 to receive a wrench, and between the inner end of said closure and a shoulder 16 in the sleeve, a gasket 17 is located. 90

When the sleeve shall have been properly adjusted to insure accurate alinement of the bolt with its points of connection with the respective boiler sheets, said sleeve will be fixedly united to the outer sheet by means 95 of a weld as indicated at 18.

Having fully described our invention what we claim as new and desire to secure by Letters-Patent, is:—

1. In a staybolt structure, the combination with a boiler sheet having an opening, of a bearing sleeve provided at its inner end portion with an inwardly projecting annular flange having a rounded outer portion, a staybolt having a head located in said 105 sleeve, the rounded portion of the flange forming a throat through which the staybolt passes, and an annular bearing member disposed freely between the bolt head and said flange. 110

2. In a staybolt structure, the combination with a boiler sheet having an opening, of a bearing sleeve having initial universally movable mounting in said opening and having an inwardly projecting annular flange, a bolt having a head located in said sleeve, a bearing member freely disposed within the sleeve between said annular flange and bolt head, and means securing 10 said sleeve to the boiler sheet.
3. In a staybolt structure, the combination with a boiler sheet having an opening, of a bearing sleeve having initial universally movable mounting in said opening,

said sleeve having an inwardly projecting 15 flange, a bolt having a head located in said sleeve, an annular bearing member having a seat at one end for the bolt head and mounted at its other end on said annular flange of the sleeve, and a weld uniting said 20 sleeve to the boiler sheet.

In testimony whereof, we have signed this specification in the presence of a subscribing witness.

BENJAMIN E. D. STAFFORD.
ETHAN I. DODDS.

Witness:

EDWIN S. RYCE.
